(57) **CLAIM**

The ornamental design for a positive airway pressure device, as shown and described.

DESCRIPTION

FIG. 1 is a front perspective view for a positive airway pressure device, according to our new design;

FIG. 2 is a rear perspective view thereof;

FIG. 3 is a front side view thereof;

FIG. 4 is a rear side view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front perspective view thereof; shown in an environment.

The shading in the figures is for illustrative purposes only and form no part of the claimed design.

In the drawings, the dash-dash-dash broken lines are for the purpose of illustrating portions of the positive airway pressure device that form no part of the claimed design. In FIG. 9 the dash-dot-dash broken lines are for the purpose of illustrating environment only and form no part of the claimed design.
